ATTORNEY

UNITED STATES PATENT OFFICE.

MOSIER SIKIRICA, OF FORT BARRANCAS, FLORIDA.

LANDING DEVICE FOR AEROPLANES.

1,305,312.

Specification of Letters Patent. Patented June 3, 1919.

Application filed February 13, 1918. Serial No. 216,862.

To all whom it may concern:

Be it known that I, MOSIER SIKIRICA, a citizen of the United States, residing at Fort Barrancas, in the county of Escambia and State of Florida, have invented certain new and useful Improvements in Landing Devices for Aeroplanes, of which the following is a specification.

This invention relates to landing devices for aeroplanes for lessening the shock and jar to an aeroplane incident to landing when descending from a flight, and has for its principal object the provision of a wheeled frame secured upon the under side of the aeroplane body by resilient means, which absorb the shock when said frame strikes the ground upon landing and thus removes or lessens the injury to the various delicate parts of the plane which often results when the plane descends too rapidly.

With this object in view, the invention consists in the novel construction, combination and arrangement of parts hereinafter described, pointed out in the appended claims and illustrated in the accompanying drawings, in which,

Figure 1 is a side elevation of a portion of an aeroplane with the improved landing mechanism applied thereto.

Fig. 2 is a front elevation of the same, and Figs. 3 and 4 are enlarged sectional views showing details of the invention.

In the drawing, 10 indicates the body of an aeroplane, on the under side of which is mounted the landing device which, in the present instance, includes a cross shaft 12 on the ends of which are mounted two wheels 13, the tires 14 of which are preferably of the pneumatic type as shown. Mounted on each end of the shaft 12 within the wheels 13, is an upright bar or rod 15, said bars being fixed or journaled on the shaft 12 as conditions warrant. The upper ends of the bars 15 are longitudinally slidable in bearings 16 secured to opposite sides of the body 10, the upper end of the bars being forked as shown at 17. Between the upper ends of each fork 17 is a cross rod 18 joining said ends, and connected to said rod between the forks is a coil spring 19. The springs 19 extend downwardly from said cross rods and are connected at their lower ends by bolts or other fastenings to the body 10.

Projecting forwardly from the center of the shaft 12 to which it is pivoted, is a shoe 21, said shoe extending forwardly for some

distance in a straight line, but, finally terminating with an upwardly curved end 22. At a suitable point in the length of the shoe 21, there is pivoted to said shoe an upwardly and rearwardly inclined bar 23, the upper end of which is forked at 24 similar to the upper ends of the bars 15. A cross rod 25 connects the upper ends of the fork 24 and a coil spring 26 attached to said cross rod extends downwardly in line with the bar 23 for a suitable distance to be connected at its lower end to a finger projecting forwardly between the fork-arms from a bracket 27 secured on the under side of the aeroplane 70

In operation, when the wheels 17 contact with the ground upon the descent of the aeroplane, the bars 15 slide upwardly in the bearings 16 and expand the springs 19 thereby forming a cushioning or yielding means for absorbing the shock of landing. Should the aeroplane descend at an angle with its forward end depressed, the shoe 21 would first engage the ground and force upwardly 80 the bar 23, expanding the spring 26 and so cushioning the blow. It will thus be seen that a simple, easy, and efficient means has been provided for effecting a safe and easy landing of an aeroplane. 85

What I claim is:

1. In combination with an aeroplane body, a landing device therefor comprising a wheeled frame, said frame including a bar, a guide member on the body in which the bar slides, above the guides being bifurcated and having a connecting member, a spring fastened to the connecting member and to the body, and said spring functioning to normally maintain the bifurcated portion in engagement with the guide member and to act as a cushion during landing of the body. 90

2. In combination with an aeroplane body, and a bracket secured thereto and having a forwardly projecting finger, a landing device comprising a wheeled frame, a bar rising therefrom and having its upper end forked and the fork-arms passing astride said finger, a cross rod connecting the fork arms, and a spring connecting the finger and 100 cross rod. 105

3. In combination with an aeroplane body, a landing device therefor comprising a wheeled frame, said frame having slidable upstanding bars, cushioning means connecting said bars to the body, said frame having a shoe, a bar connected to said shoe, the 110

- last mentioned bar having a slot, a fastening member extending into the slot, a bracket secured to the body and extending into the slot below the fastening member, and a cushioning spring disposed in said slot and secured to the fastening member and said bracket. 5
4. In combination with an aeroplane body, a landing device therefor comprising a 10 wheeled axle, bars extending upwardly from said axle to opposite sides of said body, the upper ends of said bars being forked, a bearing on each side of said body through which bearing said bars are adapted to slide 15 longitudinally, a rod connecting the upper ends of each of said forks, a spring connected to each rod and to the body, a forwardly projecting shoe journaled at one end
- on said axle and having its opposite end curved upwardly, a bar pivotally mounted 20 near the forward end of said shoe and extending upwardly therefrom with a rearward inclination, a fork on the upper end of said rod, a bracket fixed to the bottom of the aeroplane body and having a finger extending through the fork on said inclined bar, and a spring connected to said finger and to a rod extending across the upper ends of said fork. 25
- In testimony whereof I affix my signature 30 in presence of two witnesses.

MOSIER SIKIRICA.
